UNITED STATES PATENT OFFICE.

ARTHUR J. VAN DOLAH, OF LINNTON, OREGON.

CRATE.

1,104,582.

Specification of Letters Patent. Patented July 21, 1914.

Application filed May 16, 1911. Serial No. 627,492.

To all whom it may concern:

Be it known that I, ARTHUR J. VAN DOLAH, a citizen of the United States, residing at Linnton, in the county of Multnomah, State of Oregon, have invented certain new and useful Improvements in Crates; and I do hereby declare the following to be a full, clear, and exact description of the invention, such as will enable others skilled in the art to which it appertains, to make and use the same.

This invention relates to crates which may be quickly set up for use and readily knocked down and folded compactly for transportation or shipment.

A further object of the invention is to construct a crate of this class, which when set up or folded the parts of the same may be clamped in a manner to prevent said parts from becoming dislodged accidentally.

In the drawings:—Figure 1 is a top plan view of the crate. Fig. 2 is a side elevation. Fig. 3 is an end view. Fig. 4 is a transverse sectional view. Fig. 5 is a top plan view showing the crate in its folded or knocked down position. Fig. 6 is a fragmentary view, partly in section to clearly show the manner of connecting the rotary latches. Fig. 7 is a similar view showing the manner of mounting the pivot pins.

Referring to the drawings, the numeral 1 designates the sides of the crate and 2 the ends thereof. The sides and ends are formed from a plurality of horizontally arranged bars 3, the ends of said bars being arranged in overlapping relation and provided with apertures through which are passed pivot pins 4, said pins having heads 5 formed at their upper ends, and their lower ends bent at right-angles, whereby said pins are secured in their proper position. Hingedly connected to one of the uppermost side bars is a top 6, said top having each of its ends provided with slots 7, in which are engaged rotary latches 8, said latches being secured in the upper face of the end bars, and are provided with right-angle extensions 9, said latches being adapted to rotate to hold the top in its fastened position when the crate is set up. A slot 10 is formed in the front edge of the top 6 the purpose of which will be hereinafter described. A latch 10' similar to those hereinbefore mentioned is secured in the outer uppermost side bar and is adapted to be swung in a position over the front edge of

the top 6. It will be noted that the top 6, when the crate is in its set up position, rests upon the uppermost end bars and between the uppermost side bars and the upper face 60 of the same is arranged on a plane with the upper faces of the side bars.

A bottom 11 is hingedly connected to the lowermost side bar, and like the top is provided at its opposite ends with slots 12, 65 for engaging with rotary latches 13, said latches being secured to the lowermost end bars and are formed in a manner similar to the latches 8 hereinbefore mentioned. The bottom is provided with a slot 14 in its 70 rear edge, the purpose of which will be hereinafter described.

To the outer uppermost horizontal bar and to the lowermost rear horizontal bar are secured rotary latches 15, said latches being 75 formed in a manner similar to those hereinbefore mentioned. The latch secured to the uppermost bar is adapted to engage with the slot 14 formed in the bottom and the latch 15, secured to the lowermost bar is 80 adapted to engage with the slot 10 formed in the top 6 when the crate is collapsed or folded, thereby holding the top and bottom securely upon the side bars.

From this construction it will be seen that 85 a crate has been produced wherein the sides and ends are arranged in spaced parallel relation, thereby producing a crate which is especially adapted for shipping fruits and vegetables and one which may be quickly 90 and conveniently folded or knocked down for shipment, and when in such condition will occupy a very little space, and one in which the top and bottom are held securely in place upon one of the sides thereby preventing the same from becoming displaced 95 and having the hinges broken during rough handling of the same necessitated through shipment.

What is claimed, is:—

A folding crate comprising pivotally connected side and end members, top and bottom members oppositely hinged to the side members and foldable against the latter respectively when the crate is knocked down, 105 said top and bottom members being provided with recesses in each end and in their free edges, pins rotatably mounted in the end members at the top and bottom of same, said pins having laterally directed outer 110 ends and the shanks of said pins being movable freely through the recesses in the top

and bottom members respectively as said
crate is knocked down and set up and the
ends of said pins being further adapted to
overlie the top and bottom members when
5 the pins are rotated to dispose the ends
transversely of said recesses whereby the
top and bottom members are locked against
movement from set up position, and pins
rotatably mounted in the side members re-
10 spectively and disposed in a plane at right
angles to said side members, said pins hav-
ing laterally directed ends and the shanks
of said pins being freely movable through
the recesses in the free ends of the top and
15 bottom members respectively when the top

and bottom members are moved to knocked
down position and adapted to overlie the
top and bottom members when the pins are
rotated to dispose the outer ends thereof
transversely of the recesses in the free ends 20
of the top and bottom members whereby the
latter are locked against movement from
knocked down position.

In testimony whereof, I affix my signature,
in presence of two witnesses.

ARTHUR J. VAN DOLAH.

Witnesses:

JAMES C. WILSON,
OSCAR LINDAHL.
